W. PRELLWITZ

MOUNTING FOR CONCRETE BREAKERS

Filed Nov. 21, 1924

Patented Dec. 8, 1925.

1,564,893

UNITED STATES PATENT OFFICE.

WILLIAM PRELLWITZ, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR CONCRETE BREAKERS.

Application filed November 21, 1924. Serial No. 751,208.

To all whom it may concern:

Be it known that I, WILLIAM PRELLWITZ, a citizen of the United States, a resident of Easton, county of Northampton, and State of Pennsylvania, have invented a certain Mounting for Concrete Breakers, of which the following is a specification, accompanied by drawings.

This invention relates to an apparatus for breaking concrete, asphalt pavement and the like and more particularly to mountings for fluid actuated concrete breakers of the hammer type.

One of the objects of the invention is to mount a concrete breaker in a manner which will permit the operator to transport the device easily and apply great force to the tool with relatively little exertion on his part.

Another object of the invention is to provide flexibility in the mounting whereby the tool though tending to center itself may be twisted and manipulated in substantially the same manner as concrete breakers which are adapted to be hand-held.

Other objects of the invention will be in part obvious and in part pointed out in the following description taken in conjunction with the accompanying drawings in which,

Figure 1 is a side elevation of a mounted concrete breaker constructed in accordance with the practice of the invention, parts being in section to more clearly show the details of construction,

Figure 2 is a front view of the machine also partly in section.

Referring to the drawings the concrete breaker comprises a pair of wheels A having an axle B to which are attached a pair of rearwardly extending handles C supporting a pneumatic hammer D. Preferably the hammer D is located between the wheels A and the ends of the handles C so that by pressing down at the ends of the handles the hammer is forced down. Any suitable form of steel may be inserted in the hammer D as for instance the pointed drill or chisel E which is adapted to split off concrete in blocks as shown at F. In order to balance the pneumatic hammer D on the handles C, counter weights G may be provided supported forwardly of the axle B. If desired, the counter weights G may be supported by the bolts H which pass

through the clamps J and the axle B to fasten the handles C rigidly on the axle B.

In practice, it is desirable to support the hammer D flexibly on the handles C for the reason that the blocks as shown at F may then be pried loose by manipulating the handles C either sidewise or backward and forward. As shown at Figure 1 the steel E may be used to pry the block F loose from the foundation by pushing forward or back on the handles C as with a crow bar. To this end the hammer D is provided with a universal mounting on the handles comprising a cross bar K rotatably supported in brackets L on either handle C and a pivot bolt O passing through the cross bar K and through the head P of the hammer D. Swinging motion forwardly and backwardly is permitted by rotation of the cross bar K in the brackets L and sidewise movement is permitted by the rotation of the pivot bolt O.

Means are provided to hold the hammer D in a predetermined position so that the chisel E may be directed at any desired point. The four springs Q are provided for this purpose and are attached to a collar R about the hammer D and to bolts S held on the handles C by means of brackets T.

For a more positive control of the hammer D there is provided a rod U attached to the cylinder of the hammer D and extending rearwardly to the operator's position at the end of the handles C. The operator may, by pushing or pulling at the rod U, place the point of the chisel E on any point he desires. Motive fluid is supplied to the hammer D through a suitable hose V provided with a throttle valve W near the handle C to provide a convenient control. The operation of the machine is clear from the above description, it being noted that the hammer D is transported about on the wheels A and placed approximately over the place where the concrete is to be broken. Thereafter the operator by manipulating the rod U swings the chisel E where he wishes to break off the piece of concrete and then by opening the throttle W starts operating the pneumatic hammer D. The operator feeds the chisel E into the work by resting his weight on the free end of the handles C and when the block F is cracked off, he removes it by manipulating the han-

dle C and using the chisel E somewhat as a crowbar is used to split off the block from its foundation. The hammer D, however, is not free to swing about but is normally held in an upright position by the springs Q. In wheeling the machine about the weight of the hammer D is partly counterbalanced by the weights G which relieve the operator to a large extent.

16 I claim:

1. A concrete breaker comprising a pair of wheels, an axle for the wheels, a pair of rearwardly extending handles attached to the axle, a pneumatic hammer mounted 15 pivotally on the handles, and a drill steel in the hammer to receive the blows of said hammer.

2. A concrete breaker comprising a pair of wheels, an axle for the wheels, a pair of 20 rearwardly extending handles attached to the axle, a pneumatic hammer pivotally attached to the handles, a drill steel in the

hammer to receive the blows of the hammer and springs for holding said hammer normally in predetermined position.

3. A concrete breaker comprising a pair 25 of wheels, an axle for the wheels, a pair of rearwardly extending handles attached to the axle, a pneumatic hammer, a drill steel extending into the hammer to receive the 30 blows of the hammer and a universal mounting for said hammer on said handles.

4. A concrete breaker comprising a pair of wheels, an axle for the wheels, a pair of 35 rearwardly extending handles attached to the axle, a pneumatic hammer, a drill steel extending into the hammer to receive the blows of the hammer, a universal mounting for said hammer on said handles, and spring means for holding said hammer normally 40 in a predetermined position.

In testimony whereof I have signed this specification.

WILLIAM PRELLWITZ.
